UNITED STATES PATENT OFFICE

FRANZ GOLDBERGER, OF KARLSRUHE, GERMANY

DEVICE FOR SKEINING HANKS ON THE REEL

Application filed October 19, 1929, Serial No. 400,859, and in Germany October 22, 1928.

This invention refers broadly to skeining means and it is intended to devise means of simplifying the manipulation and construction of such devices and to dispose and arrange them in such a manner that they may be readily combined with the reeling instrumentalities. In particular the invention provides for the skeining of the hanks by means of thread holders to which the skeining thread is fed from the outside of the reel and which cause this thread to be conducted between the skeins. Among other advantages and objects of the improved skeining means it may be mentioned that the thread holder of substantially plug-like construction is engaged at the inside of the reel by thread detaching and gripping means attached to a short arm or bracket and constructed in such a manner that it will admit of being pushed into the reel between two hanks. In view thereof the long rod otherwise necessary and which according to the previous art had to be inserted sideways into the reel may be dispensed with. The economy in construction and manipulation which is realized by this combination of parts combined with the possibility of being able to dispose the skeining means according to this invention directly on the reeling machine and thereby to avoid the necessity of carrying one of said devices through a distance to the other device, as heretofore generally required, constitutes a very important industrial progress in the skeining art as compared with the previous constructions.

The invention is shown on the accompanying drawing in several embodiments by way of exemplification more or less diagrammatically. In the drawing Fig. 1 is a cross-sectional view of the hank. Figs. 2 and 3 illustrate respectively in elevation with parts in section and in plan view the device and its operation according to this invention. Figs. 4, 5, 6, 7, 8 are illustrations of the different positions of the operating parts of the device

and of the hank operated upon. Figs. 9-18 illustrate a modified form of construction of the device in Fig. 9 in front elevation and in Fig. 10 in side view. Figs. 11, 12, 13, 14, 15, 16, 17 are illustrations of the different stages of operation of this modified construction. Fig. 18 is a longitudinal section of another modification to be referred to.

In Fig. 1 of the drawing the desired skeining or tying of the hank is shown diagrammatically with the hank 20 shown in section. The hank is supposed to have been previously subdivided by a kind of comb-like instrumentality into three sections. The skeining thread is indicated at 23. The principle of the invention is more particularly illustrated in Figs. 2 and 3 of the drawing, and in Figs. 4-8 the different stages of movement and positions of the plug-like thread carrier or shuttle are disclosed. It may be assumed that a large number of hanks 20 are disposed in the exemplification shown on the reel, the said hanks being slightly spaced from each other. In the exemplification represented in the drawing the actuating parts for the thread carrier S, shuttle or the like are shown to be duplicated several times to correspond to the number of hanks of the reel. But it is not absolutely necessary to dispose a plurality of such devices side by side of each other, inasmuch as all of the interior thread gripping means projecting into the reel may be mounted on a universal beam, while all the exterior thread gripping means are disposed upon an additional universal beam which is likewise common to all the thread gripping means. The last mentioned beam or rail is preferably guided by means of two special oscillating arms, so that these thread gripping means will perform the same rotary movements as the interior thread gripping means.

The several skeining means are assumed in the exemplification shown to be disposed on the arm 17 and side by side of each other,

In the direction of the axis *a*—*b* Fig. 2 the shaft 1 is arranged which is provided at its lower end with an arm 2 carrying at its outer extremity the inner thread gripping means 5 or shuttle S with the sleeve-like spring 4 mounted therein. Motion is imparted to the shaft 1 at its upper end 5. Upon the shaft 1 the sleeve or collar 6 is mounted for axial displacement and is arranged to move along the groove 8 of the shaft 1 which is engaged by the projection 7 on the collar 6, so that the collar will partake in the rotation of the shaft 1. The collar 6 carries at its lower end the arm 9 at the extremity of which the outer thread gripping device or shuttle holder 10 is provided which will therefore in all the positions of the instrumentalities be located exactly opposite the thread gripping means or shuttle holder S. The arm 9 is provided with a side arm carrying a locking pawl 21 for the thread holder. The latter can be thrown out of engagement by a cam disk operating the pawl or hook 21 at the desired moment. The sleeve 6 is surrounded by the axially displaceable sleeve or collar 11 which is guided by a projection 12 entering a groove 13 of the sleeve 6. To the upper end of the sleeve 11 a relatively fixed arm 15 is secured, so that the simultaneous rotation of the arms 9 and 25 15 is not interfered with. The entire combination is rotatably mounted in bearings 16.

The mode of operation of the device is substantially as follows. The arm 2 is disposed between two hanks and is introduced into the reel as indicated in Fig. 3. At the same time the comb 18 which is mounted on the frame 19 subdivides each particular hank in as many sections or skeins, as are to be tied by the corresponding loops of the skeining thread. The thread holder S will then assume the position of Fig. 4 of the drawing. To this holder the skeining thread is secured at 22 and with this thread it is moving downwards into the position of Fig. 5. At the same time the locking hook or pawl 21 has been opened and the thread holder S is forced into the annular spring acting sleeve 4. Now the shuttle holder 3 is moved to the position of Fig. 6 and carries the thread holder and the thread along with it. By the rotation of the sleeve 11 the arms 9 and 2 are simultaneously turned from the position A (Fig. 3) which they had assumed heretofore to the position B, and the thread holder will then have assumed the position according to Fig. 7. Upon now moving the thread holder upwards it is again inserted into the outer shuttle holding sleeve 10 and is locked in position by the locking pawl 21. In the next stage the thread holder is moved once more into a position above the yarn. By continuing the procedure described a very superior looping of the skeining thread around the hank is obtained which is equal to the normal manual skeining operation.

In Figs. 9–18 a modified form of apparatus is shown in which instead of several separate shuttle or thread holders 9, 10 rockingly disposed in guides 16 a continuous bar or rail 35 is employed which is supported at both ends by the arms 36 each of which is adapted to be rocked on an axis *c*—*d* and are moreover disposed to be displaced, or reciprocated in the exemplification shown in the direction of the axis *c*—*d*. By this arrangement substantially the same result is obtained as in the exemplification first mentioned. The rail 35 is displaced by positive means in parallelism of its initial position, so that every point on the rail will describe the same circular arc ABCD as the outer heads of the two rocking arms on which the rail 35 is suspended. The several beams or arms 9 of the exemplification first mentioned will therefore now only constitute imaginary lines and the heads 10 of the arms are replaced by the apertures 37 in the rail 35 into which the thread holders S are adapted to fit. In further pursuance of the principle of this modification the several locking or arresting hooks 21 may be replaced by a universal locking device in common to all thread holders S, as for instance by rail 38 disposed within the rail or bar 35 and of smaller thickness than the same. This rail 38 may be longitudinally displaced, and, as shown in Fig. 18 may arrest the thread holders by projecting shoulders or the like engaging lateral corresponding notches of the thread holders and adapted moreover to release the holders after a short movement of the rail 38 to the left. If the rail 38 or the projections thereof are made spring-actuated, there is no necessity of providing special regulating means for the re-engagement of the holders S therewith, because the upwardly reduced holders will be free to become snapingly engaged and retained in the proper position. For the purpose of releasing the thread holders S however the bar or rail 38 must be controlled by positive means which may for instance be effected by a grooved drum or by means of a cam 39 which are operated in the well known manner and in accordance with the requirements of the particular case.

The utilization of the bar or rail 35 to replace the several upper thread carrying means 9 and of the guiding sleeves 16 therefore will entail a corresponding arrangement of the lower thread carrying means 2 which may be mounted in a continuous bar or rail 40 the central plane of which will have to coincide with the rotating axes *c*—*d* of the two rocking arms 36 and adapted to be displaced in this plane, provided the heads 3 of the lower thread gripping means 2 are intended to describe the same circular arcs as the apertures 37. The movement should of course be such that the length *e* of the angu-

larly projecting lower arms 2 should be the same as that of the rocking arms 36. Provision should also be made that in the rocking operation the amplitudes AB, AC 5 and AD should be respectively the same in the upper and lower parts of the device, which result may for instance be produced by means of links 41 which may for instance be hinged to the upper ends of the shafts or 10 spindles 1 of the thread gripping means and which on the other hand may be inserted in spherical heads free to revolve on all sides and the centres of which are arranged in an extension of an imaginary axis of the bores 15 37. In Figs. 12 to 17 the most important parts of the movements executed by the thread holders S are shown in successive steps similar to the representation of Figures 4 to 8 of the drawing.

20 The essential feature of the new skeining device is the fact that the thread gripping means or the like is adapted to move in a circular path around an existing or imaginary axis intermittently first in one and then 25 in the other direction, and that during the interruptions of the movement the change of position of a thread holder or shuttle takes place in the downward and respectively in the upward direction in the desired 30 manner of succession, the said thread holder carrying the skeining thread along with it.

While I have described for the purpose of disclosure of my invention in some details some specific embodiments of the principles 35 of my invention, it will be apparent that numerous other modifications and changes may be made, and I, therefore, do not desire to be limited in the broader aspects of my invention to the specific construction 40 described and illustrated, except as otherwise appears from the appended claims.

I claim:—

1. Device for skeining hanks on the reel, comprising in combination a plurality of 45 thread gripping means, holders for said gripping means, and means connected with said holders and adapted to intermittently rock said thread gripping means, said connecting means being also adapted to reciprocate in 50 a direction perpendicular to the rocking movement.

2. Device for skeining hanks on the reel, comprising in combination a plurality of shuttles carrying threads, a plurality of shuttle 55 holders, locking means for automatically locking and releasing said shuttles within said shuttle holders and means connected with said holders and adapted to intermittently rock said shuttles, said connecting 60 means being also adapted to reciprocate in a direction perpendicular to the rocking movement, thereby moving said shuttles above and below the hank.

3. Device for skeining hanks on the reel, 65 comprising in combination a plurality of

shuttles carrying threads, a plurality of shuttle holders, projections automatically locking and releasing said shuttles within some of said shuttle holders, springs arranged within the remainder of said shuttle holders and permanently holding said shuttles and means connected with said holders and adapted to intermittently rock said shuttles, said connecting means being also adapted to reciprocate in a direction perpendicular to the 70 rocking movement, thereby moving said shuttles above and below the hank.

4. Device for skeining hanks on the reel, comprising in combination a plurality of shuttles carrying threads, a plurality of shuttle holders, a plurality of arms carrying said shuttle holders and arranged in pairs, each pair consisting of a rocking arm arranged above the hank and carrying one of the shuttle holders and of a rocking arm arranged under the first-mentioned arm and under the hank and carrying one of the shuttle holders, said arms being adapted to reciprocate in a direction perpendicular to the rocking movement, thereby moving said shuttles above and 80 below the hank.

5. Device for skeining hanks on the reel, comprising in combination a plurality of shuttles carrying threads, rails provided with apertures into which said shuttles are adapted to fit, rocking arms mounted in some of said rails, some of said arms being provided with apertures at their exterior ends for holding said shuttles, links connecting said rails with each other, said links being adapted to revolve freely on all sides, means for intermittently moving said rails in the direction of their axes and means reciprocating said rails in a direction perpendicular to the first- 95 mentioned direction.

6. Device for skeining hanks on the reel, comprising in combination a plurality of shuttles carrying threads, rails provided with apertures into which said shuttles are adapted to fit, rocking arms mounted in some of said rails, some of said arms being provided with apertures at their exterior ends for holding said shuttles, links connecting said rails with each other, said links being adapted to revolve freely on all sides, means for intermittently moving said rails in the direction of their axes and means reciprocating said rails in a direction perpendicular to the first- 100 mentioned direction, and locking rails having projections for arresting said shuttles, said locking rails being adapted to move within said first-mentioned rails.

7. Device for skeining hanks on the reel, comprising in combination a plurality of shuttles carrying threads, rails provided with apertures into which said shuttles are adapted to fit, rocking arms carrying said rails, other rails arranged laterally to said first- 115 mentioned rails, other rocking arms provided 120
